UNITED STATES PATENT OFFICE.

JOE H. HART, OF FILLMORE, CALIFORNIA.

ANTISANDER FOR PISTON-PUMPS.

1,379,302.

Specification of Letters Patent. Patented May 24, 1921.

Application filed January 18, 1921. Serial No. 433,094.

To all whom it may concern:

Be it known that I, JOE H. HART, a citizen of the United States, residing at Fillmore, in the county of Ventura and State of California, have invented a new and useful ⁵ Antisander for Piston-Pumps, of which the following is a specification.

This invention is applicable to pumps for pumping oil wells and water wells and is intended to prevent the sand from reaching ¹⁰ the valve of the pump.

To effect this result I have provided an attachment to be applied at the bottom of the pump tubing, and said attachment comprises a hood connected to the bottom of the ¹⁵ tubing, a working barrel connected to the hood and alined with the tubing, a sump connected to the hood and closed at its lower end, there being lateral inlets to the upper ²⁰ part of the sump, said sump being closed at the bottom; and a shell connected to the hood and provided with an inlet at the bottom at a distance below the bottom of the sump. The inlet to the sump is preferably ²⁵ through lateral orifices in the hood, and the working barrel is provided inside the sump with a foot valve, and inside of said working barrel the valved plunger operates in the same manner as is common with ³⁰ piston pumps.

A principle of this invention is that the liquid flowing from the well casing to the pump tubing, reaches the foot valve of the pump after passing through a settling passage that extends a considerable distance ³⁵ above an opening that serves the double purpose of an inlet for liquid and an outlet for sediment if any, settling from the liquid, and the flow of said liquid into the ⁴⁰ pump tubing through the foot valve of the pump is subjected to a frictional resistance at said foot valve, which is greater than the frictional resistance at any point between the casing and the foot valve; and the inlet to the ⁴⁵ foot valve is through a restricted passage at a considerable distance above the inlet from the casing; so that the flow of oil through the foot valve, either at the upstroke of the piston or by the force of gas from the well, will be ⁵⁰ restricted at the top of the settling passage, and will be still more restricted at the foot valve; so that while there is no resistance that is effective to limit the flow to the pump tubing except such resistance as occurs at ⁵⁵ the foot valve. There is such resistance to

the flow of the liquid from the settling passage either under the suction of the pump, or under gas pressure, as will prevent the liquid containing solids of heavier specific gravity than the liquid, from being carried to the ⁶⁰ foot valve. That is to say such solids are not subjected to such current as will carry them to the top of the settling passage.

This is effected by locating the foot valve inside a sump which is closed at the bottom, ⁶⁵ and throughout from bottom upward to sump inlets which are sufficiently elevated above the inlet from the source of oil supply as to allow the solids to settle by gravity and fall into the bottom of the well as the ⁷⁰ liquid turns from its downward course outside the shell, to the opening at the bottom of the shell.

Objects are cheapness, simplicity, strength and durability, and automatic precipitation ⁷⁵ of the sand from the liquid.

This invention is applicable inside a well casing having a perforated portion through which the liquid flows from the formation, and a portion below such perforated portion ⁸⁰ through which the liquid does not flow, and comprises a combination with such casing a shell extending a considerable distance down inside the casing below the perforations so as to form a settling chamber between the ⁸⁵ shell and the casing, said shell having an inlet at its lower end; and means to restrict the flow of liquid from the casing to the foot valve of the pump, said foot valve being adapted to further restrict such flow to the ⁹⁰ working below the pump.

Other objects, advantages and features of ⁹⁵ invention may appear from the accompanying drawing, the subjoined detail description and the appended claims.

The accompanying drawing illustrates the invention.

Figure 1 is a fragmental elevation of an anti-sander constructed in accordance with this invention and installed in a well casing, ¹⁰⁰ a fragment of which is shown below oil level.

Fig. 2 is a fragmental axial section on line ¹⁰⁵ α^2 , Fig. 1, showing oil and subsiding solids such as sand, and the parts in position as when the well is gassing under heavy pressure. The arrows indicate the direction of gas pressure and flow.

Fig. 3 is a view of the hood and the collar, and fragments of the working barrel, ¹¹⁰

the pump tube and the standing valve, connected together and detached from the other parts of the appliance.

Fig. 4 is a bottom view of what is shown in Figs. 1 and 2, omitting the oil.

Fig. 5 is a section on line x^5-x^6 , Figs. 1 and 2, looking up in the direction of the solid arrows, and omitting the oil.

Fig. 6 is an analogous section on said line x^5-x^6 , looking down as indicated by the broken arrows.

Fig. 7 is an axial section of the hood detached.

Fig. 8 is a fragmental developed elevation of the hood.

The pump tubing 1 and casing 2 are of usual construction, and the hood 3 is connected to the pump tubing 1 by a suitable coupling as indicated by the collar 4. Said hood is preferably provided with a threaded socket 5 centrally arranged in the top of the hood and terminating in a bore 6 through which the working barrel 7 extends to the collar 4 into which it is screwed. The working barrel 7 is provided at its bottom with the usual standing or foot valve 8 which is normally removably seated at the bottom of the working barrel. Inside the working barrel is the usual valved piston 9.

The body of the hood is externally screw threaded as at 10, below a shoulder 11 against which the shell 12 abuts when screwed home upon the external threads 10.

Below the external threads 10, the hood is reduced to form a skirt 13 which is internally threaded and into which is screwed the open top sump 14 that extends down inside shell 12 and is closed at its bottom and from bottom to its top. The skirt has a lateral inlet formed by openings 15 that communicate with the top of the settling chamber 16 formed between the outside of the sump and the inside of the shell. Said shell is provided at its bottom with an orifice 17 which serves to admit oil to the settling chamber 16 and to allow solids of greater specific gravity than the oil to discharge toward the bottom of the well.

The sump 14 extends down in the shell below the inlets 15; and, in conjunction with the skirt, forms a pump supplying chamber containing the working barrel 7 which fits reduced portion 18 of the bore 6 in the hood, just below the collar 4 that is internally threaded throughout to receive at its upper end, the pump tubing 1 on which the collar is screwed, and at its bottom, the working barrel 7. Said collar is externally threaded at the lower end, as at 10 to screw into socket 5.

The hood thus forms a connection to which is fixed the pump tube 1, the shell 12, the sump 14 inside the shell; a working barrel 7 inside the sump, and fixed to, and extending down from the hood and fitted

with the foot valve 8 and also with the piston 9 operated by the pump rod 19, and connected to the foot valve by the Garbutt attachment 20 if it is desired to have such attachment for pulling the foot valve.

It is important that the combined inlet and outlet 17, the ascending passage 16, and the transverse inlet 15 shall have practical relative proportions that will allow the oil to flow to the sump without such agitation caused by suction of the pump or pressure of gas from the well, as might draw sand-laden oil into the sump.

If the orifice of the foot valve 8 which is seated in the lower end of the working barrel, is one inch in diameter, the combined cross-sectional area of the lateral holes 15 must be greater than the area of the orifice of the foot valve.

The orifice in the bottom of the shell must have a cross-sectional area greater than the cross-sectional area of the lateral holes in the hood for free flow so as to allow the liquid to flow into the bottom of the shell by gravity, and to allow all sediment to 85 freely escape under the same force.

The cross-sectional area of the inlet to the shell is less than the cross-sectional area of the passage between the shell and the inside well. The combined cross-sectional area of the lateral orifices in the hood is less than the cross-sectional area of the inlet to the shell and the cross-sectional area of the passage between the sump and the working barrel must be greater than the combined cross-sectional areas of the orifices forming the inlet to the sump.

Assuming that the apparatus shown in the drawings is applied to what is called a two inch pump, the orifices 8 at the foot valve 105 would be $\frac{1}{8}$ of an inch in diameter; the lateral orifices 15 being six in number would be of a somewhat greater combined area, and the inlet at 15 would be $\frac{6}{10}$ of a square inch. The diameter of each of the six holes 15 110 should be about $\frac{3}{8}$ of an inch.

The opening 17 at the bottom of the shell may be of any desired size providing it is sufficiently greater in cross-sectional area than the cross-sectional area of the orifices 115 15 to prevent such upward flow of liquid through the opening 17 as to form a current to carry solids upward.

The shell, around the margins of the inlet 17 is curved inwardly as at 21, toward such 120 inlet, so that in case the well should gas, the gas, being lighter than the liquid, will follow such curve in undisturbed flow, and enter the inlet at the rim thereof while the oil that enters the shell does so at the center 125 of opening 17 after passing below the gas.

The length of shell required below the perforations forming the inlets 22, to the well casing, may be determined by taking a quantity of the sanded liquid pumped from 130

the well in the usual way and shaking it in a test tube of determined length until the solids are well distributed through the liquid, and then standing said tube on end 5 and noting the length of time required for the solids to entirely settle to the bottom of the tube, and then constructing a shell, 12, of such length as to accommodate in the passage 23 between it and the casing, an amount 10 of oil greater than that which might be made to pass through the foot valve inlet 8, either by suction or by gas pressure of the well during the period in which the solids suspended in the liquid will settle to the bottom 15 of the shell.

The result attained by such construction is that the lateral flow of liquid from the downwardly produced annular extension of passage 21 to the opening 17 is not such as 20 to carry over to said opening any of the heavy solids.

I claim.

1. The combination with a well casing having an imperforate portion and a perforate portion; of a pump having a foot valve and an orifice therefor; a shell connected to the pump and extending down below the pump within the imperforate portion of said casing, and having an inlet at 25 its lower end, and being otherwise closed to the interior of the casing; and means arranged within the casing between said pump and said inlet and adapted to restrict the flow of liquid from the space within the shell 30 to the foot valve orifice; said shell being of considerable length below the perforations of the casing to allow solids to settle inside the casing substantially as and for the purpose set forth.

40 2. The combination with a well casing having an imperforate portion and a perforate portion; of a pump having a foot valve and an orifice therefor; a shell rounded at its

lower end and connected to the pump and extending down below the pump within the imperforate portion of said casing, and having an inlet at its lower end, and being otherwise closed to the interior of the casing; and means arranged within the casing between said pump and said inlet and adapted to restrict the flow of liquid from the space within the shell to the foot valve orifice; said shell being of considerable length below the perforations of the casing to allow solids to settle inside the casing substantially as and for the purpose set forth.

3. An anti-sander comprising a shell having an inlet at the bottom; a sump inside the shell and closed at the bottom; a hood to which the shell and the sump are connected; there being a passage between the shell and the sump and an outlet from such passage into the sump; and a working barrel having a foot valve open to the sump; the orifice of the foot valve being of less cross-sectional area than the orifice of said outlet; and the cross-sectional area of the orifice of said outlet being less than the cross-sectional area of the orifice of the inlet at the bottom of the shell.

4. An anti-sander comprising a shell having an inlet at the bottom; a sump inside the shell and closed at the bottom; a hood to which the shell and the sump are connected; there being a passage between the shell and the sump and an outlet from such passage into the upper part of the sump; and a working barrel having a foot valve open to the sump.

In testimony whereof, I have hereunto set my hand at Los Angeles, California, this 10th day of January, 1921.

JOE H. HART.
